ATTORNEY.

UNITED STATES PATENT OFFICE.

JOSEPH H. MANON, OF ST. JOSEPH, MISSOURI.

REFRIGERATOR.

940,700.

Specification of Letters Patent. Patented Nov. 23, 1909.

Application filed November 30, 1908. Serial No. 465,269.

To all whom it may concern:

Be it known that I, JOSEPH H. MANON, a citizen of the United States, residing at St. Joseph, in the county of Buchanan and State 5 of Missouri, have invented certain new and useful Improvements in a Refrigerator, of which the following is a specification.

The object of my invention is to provide a refrigerator having a scale mechanism by 10 which the customer is shown exactly the weight of the ice he receives at each delivery thus enabling the customer to secure the full amount of ice for which he pays.

I accomplish my object by the mechanism 15 illustrated in the accompanying drawings, in which,—

Figure 1 is a side view of the refrigerator, broken away, showing a sectional elevation of scale; placed in position; Fig. 2 is a 20 front elevation of the refrigerator; Fig. 3 is a detail transverse sectional elevation of said scales; Fig. 4 is a detail cross sectional elevation of the same; Fig. 5 is a top view of the platform with drains and pipe to carry 25 off the waste water, and Fig. 6 is a sectional view of a trap for said waste water.

Similar letters refer to similar parts in the several views.

In the drawings A is the frame of a 30 refrigerator and A' is the hinged top thereof.

B is the top of the scales constituting a platform upon which ice B' is placed.

B² B² are drains to carry the water from 35 said platform to a waste pipe b, which pipe will vary in its position vertically according to the weight of the ice that may be placed on platform B.

C is a trap into which waste water empties from pipe b.

C' is a pipe that carries said waste water 40 from trap C into any suitable receptacle placed under the refrigerator.

b' shows the waste water in trap C which prevents warm air from entering waste pipe b and which thus prevents the loss of ice from warm air.

C² is an outlet provided with a screw cap C³ to permit the cleaning of said trap.

D D are doors into apartments in the refrigerator.

E is a metal frame inclosing and protecting the scales.

F F are supports, preferably cast iron, for guides F' F' and for the top of spiral steel spring H. Said spring H carries platform 55 B up automatically and propels the dial hand H'. Said cast iron supports F F are cast integral and rigidly fastened to the base of the scale inclosure.

I is an adjustment rod connected with a 60 worm gear I' at its inner end, its outer end I² serving as a thumb screw to gage the tension of spring H, thus showing the weight of the load carried on platform B before a new supply of ice is added. The exact 65 amount of the new supply of ice which is added is thus shown.

J is a rod connected at its inner end with worm gear J' which rod is propelled by straight rack K, which is supported by 70 guides F' F'.

L L are supports for platform B.

M is a cross bar serving as a support for cog wheel J'; it is connected to guide support F by means of bolts f f at either end.

O is a water cooler of galvanized iron, or any suitable metal, which is removable similarly to a desk drawer; the object in its being removable is to allow a convenient way for filling the same with water.

P is a bracket to support a tumbler at the side of the water cooler O and is rigidly attached to frame A of the refrigerator. Said water cooler is provided with a faucet R.

What I claim and desire to secure by Letters Patent, is:—

The combination with the frame of a refrigerator, of a platform, a scale inclosure below the same, duplicate supports having 90 rigid connection with the bottom of the platform, supports rigidly fastened at the base of the scale inclosure, guides pivotally connected with said platform supports and with the supports on the base of the scale 95 inclosure, a spiral spring engaging at its

lower end with the base of the platform supports and at its upper end with the connecting part of the tops of said supports rigid on the bottom of the scale inclosure, an adjusting worm gear, a cross bar, a straight cog connected perpendicularly to said cross bar, a scale dial and hand on the outside of the refrigerator, a cog wheel, a rod connected with said cog wheel and said dial hand, a thumb screw outside the refrigerator and

an adjustment rod connected with said worm gear and with said thumb screw, substantially as set forth and shown.

In testimony whereof I affix my signature in presence of two witnesses:

JOSEPH H. MANON.

Witnesses:

JOHN CORBY,
HARRY BAUM.
